CAN GRID

Filed Sept. 6, 1928

UNITED STATES PATENT OFFICE

NORMAN M. SMALL AND LEON BUEHLER, JR., OF WAYNESBORO, PENNSYLVANIA, ASSIGNORS TO FRICK COMPANY, OF WAYNESBORO, PENNSYLVANIA, A CORPORATION OF PENNSYLVANIA

CAN GRID

Original application filed October 6, 1925, Serial No. 60,896. Divided and this application filed September 6, 1928. Serial No. 304,278.

Our invention relates to a can basket such as is used in ice making for holding a set of cans while the ice is formed therein and is a division of our application No. 60,896, filed October 6, 1925, which has matured into Patent No. 1,689,060, dated October 23, 1928. It is desirable in such an operation to hold the set of cans rigidly in relation to one another until the freezing operation is completed and thereafter to manipulate the entire set simultaneously to dump the blocks of ice. Among the objects of the invention are to provide improved means for introducing air into the cans to produce clear ice and for reducing the pressure of the air passing into the cans.

Referring to the accompanying drawings which are made a part hereof and on which similar reference characters indicate similar parts,

Figure 1 is a perspective of a can grid with cans therein as used in a medium or high pressure system, parts of the cans being broken away or omitted for the sake of clearness,

Figure 2, a detail showing a connecting device in front elevation looking across the can grid,

Figure 3, a side elevation of the same device,

Figure 4, a section on line 4—4 of Figure 2,

Figure 5, a section of a connector at the end of the can grid,

Figure 6, a section similar to Figure 4 but showing a modified form of connection, and

Figure 7, a section on line 7—7 of Figure 6.

In the drawings reference character 10 indicates the side members of the can grid, said members being spaced from each other and secured together by means including upper spacers 11 arranged at intervals along the length of the can grid. Lower spacers 12 are arranged at the extreme lower edges of side members 10, so as to encircle each can and support the same against relative downward movement by engagement with a flange 13 at the upper end of the can 14 secured to or made integral with the can and resting on the lower spacers 12 as clearly indicated in Figs. 2 and 3. This feature enables us to use a can of standard depth instead of a special deep

can as used in all so-called can grid systems with which we are familiar. Horizontal bars 15 are secured, as by means of screws made of brass or other non-rusting material, to the side members at a little distance above the spacers 12 said bars serving to hold the cans rigidly in place against upward movements away from said spacers. The screws being non-rusting, the bars can readily be removed at any time.

It will be understood that the parts hitherto described constitute in effect a single unit and may be manipulated as such, the can grid being positioned as a whole in the freezing compartment and when the freezing operation has been completed being lifted, dipped in warm or hot water and tilted so as to dump all the blocks of ice at one time.

For introducing air into the cans adjacent the lower end thereof we provide means comprising an air pipe or header extending lengthwise of the can basket and here shown as secured to one of the members 10. This conduit is formed so as to lie flat against the side member and as here shown may be rectangular in section. Adjacent each can we have provided a brass fitting 17 which is secured by screws 18 to a side member 10. The screws are located one above and one below the air header and clamp the fitting 17 against the header in a manner to hold the header securely against the side member 10.

A rubber gasket 19 is interposed between the header and the fitting said gasket having a passage registering with a port in the wall of the header and with a passage 20 extending horizontally into the fitting. A vertical passage 21 extends upward at the end of the passage 20 and this in turn communicates with another horizontal passage 22 from which the air emerges into a downwardly inclined passage 23 connected by a pipe composed of a plurality of sections of rubber or metal 24, 25, 26 and 27 to any suitable port near the bottom of the can. Ordinarily the section 24 will be made of metal and will have a threaded or other tight fit in the passage 23 while the section 25 will be of rubber stripped over the end section 24.

In order to reduce the pressure of the flow

of the air to the ice cans I provide a removable screw plug 28 in the vertical passage 21 communicating with the can and said removable screw plug has a transverse passage which registers with the transverse passage 22. The lower end of the transverse passage in the screw plug is reduced at 29 which serves to perform the desired function. It will be understood that the fitting 17 has a three-fold function in that it helps to secure the header 16 to the can grid, supports the rubber tube 25 and connected parts and on account of the removable screw plug 28 has a pressure reducing device for the air. The plug 28 may be removed for cleaning and to remove stoppage.

In the preferred form of the invention a fitting 30 is provided adjacent one end of the header said fitting being held in place by a pair of screws 18 and having a passage 31 registering with a port in the header, a rubber gasket being interposed between said devices at the junction of said port and passage. The fitting 30 has circumferential threads at 32, as usual, for holding the end of a rubber hose 33 in place.

In the operation of the device so far described air is admitted through the hose 33, thence through the passage 31 in fitting 30 to the header 16 from which it emerges through the lateral ports into the various fittings 17 and it goes thence into the pipes leading to the bottom of the respective cans where it bubbles up through the water in well-known manner for the familiar purpose of causing the water to form clear ice in freezing. The function of screw 28 of a fitting is obviously for the purpose of clearing the air passage of any clogging that is liable to occasionally take place within the screw by reason of the reduced passage at 29. When this occurs the screw can readily be removed and cleaned.

In the modified form of Figures 6 and 7 we have shown a device similar to that of Fig. 4 by the employment of which the need for a connection such as shown in Figure 5 is eliminated. The fitting 34 shown in these figures is held in place by screws 18 and is provided with a gasket 19 having an opening registering with the port in the header 16 and a passage 35 in the fitting. The fitting is provided with an expanded nozzle having circumferential threads at 36 as in Figure 5 to support an air supply hose. A passage leads upward, then horizontally and then obliquely downward from the passage 35 substantially as in Figure 4 for connection to a pipe leading downward into a freezing can as above described and this passage is provided with a screw 28 substantially as previously described. When this device is used a supply hose is connected to the nozzle and air enters by the passage 35 passing thence in part to the header and in part to the passage lead-

ing to the freezing can corresponding to the fitting in question. It will be seen that the single fitting 34 takes the place of the fitting 30 and one of the fittings 17 in Figure 1.

It will be obvious to those skilled in the art that various changes may be made in our device without departing from the spirit of the invention and therefore we do not limit ourselves to what is shown in the drawings and described in the specification but only as indicated in the appended claims.

Having thus fully described our said invention, what we claim as new and desire to secure by Letters Patent, is:

1. A can grid comprising means for holding a set of cans including a member extending alongside the set of cans, a header rectangular in section lying against said member, a plurality of fittings straddling the header, means for securing the fittings to said member, means for supplying air to the header, pipes extending from the fittings into the cans, passages leading through a wall of the header and through the fittings to said pipes, and pressure reducing means in said passages, substantially as set forth.

2. A can grid comprising means for holding a set of cans including a member extending alongside the set of cans, a header rectangular in section lying against said member, a plurality of fittings straddling the header, means for securing the fittings to said member, means for supplying air to the header, pipes extending from the fittings into the cans, passages leading through a wall of the header and through the fittings to said pipes, and pressure reducing means in said passages comprising a screw having a longitudinal passage of reduced diameter adapted to register with different parts of the passage in the fitting, substantially as set forth.

3. A can grid comprising means for holding a set of cans including a member extending alongside the set of cans, a header opposite said member, a plurality of fittings straddling the header, means for securing the fittings to said member, means for supplying air to the header, pipes extending from the fittings into the cans, passages leading through a wall of the header and through the fittings to said pipes, and pressure reducing means in said passages comprising a screw having longitudinal and transverse passages adapted to register with different parts of the passage in the fitting, substantially as set forth.

4. A can grid comprising means for holding a set of cans including a member extending alongside the set of cans, a header rectangular in section lying against said member, a plurality of fittings straddling the header, means for securing the fittings to said member, means for supplying air to the header, pipes extending from the fittings into the cans, passages leading through a wall of

- the header and through the fittings to said pipes, and means for reducing pressure of air passing through said air supplying means, substantially as set forth.
- 5 5. A device of the class described comprising a frame, means carried by the frame for supporting a plurality of ice cans, an air header extending along said frame, tube connections secured against and extending from 10 the header, a plurality of tubes attached to said connections and extending downward within said cans, and means for reducing the pressure of air passing through the tube connections, substantially as set forth.
- 15 6. A device of the class described comprising a frame, means carried by the frame for supporting a plurality of ice cans, an air header extending along said frame, tube connections secured against and extending from 20 the header, a plurality of tubes attached to said connections and extending downward within said cans, and means for reducing the pressure of air passing through the tube connections comprising a removable plug, pro- 25 vided with a passage of a size smaller than the air passage from the header, substantially as set forth.
7. A device of the class described comprising a frame, means carried by the frame for supporting a plurality of ice cans, an air header extending along said frame, a plurality of tube fittings straddling said header serving as outlets and as means for securing the header to said frame, a plurality of tubes 30 extending from said fittings into the cans, and means for reducing the pressure of air passing through said tubes, substantially as set forth.
- 35 8. A device of the class described comprising a frame, means carried by the frame for supporting a plurality of ice cans, a header rectangular in cross section lying on the inner side of said frame, a plurality of tube connections adapted to secure said header in 40 place and serve as outlets from said header, a plurality of tubes extending downward within said cans from said tube connections, and means for reducing the pressure of air passing through said tube connections, said 45 means comprising a removable screw plug, substantially as set forth.
- 50 55 In witness whereof, we have hereunto set our hands at Waynesboro, Pennsylvania, this 23rd day of August, A. D. nineteen hundred and twenty-eight.

NORMAN M. SMALL.
